AUTOMATIC LIQUID VENDER

John M. Alexander, Lincoln, Nebr.

Application January 8, 1932, Serial No. 585,513

2 Claims. (Cl. 221—103)

My invention relates to automatic liquid dispensers which are latched against operation and which may be unlatched only by the insertion of a coin of the proper denomination.

One of the objects of the invention is the provision of a hand or power operated pump for dispensing a liquid, the pump being latched automatically and being releasable from its latched position through the intermediary of a coin.

Another object of the invention is the provision of a releasable latch for a pump, the pump being arranged to automatically resume its usual position after the completion of the pumping stroke and the latch being automatically oper-

able for preventing a second pumping stroke until another coin of the proper denomination has been inserted.

Another object of the invention is the provision of a latch for a pump with a second latch to engage the first mentioned latch for temporarily holding it out of latching engagement.

Another object of the invention is the provision of a pump having a pinion and a rack with opposed ratchets on the pinion shaft and pawls for engaging the ratchets one at a time, the pawls being shifted into and out of engagement with the respective ratchets through the up and down strokes of the pump.

Having in view these objects and other which will be pointed out in the following description, I will now refer to the drawing, in which

Figure 1 is a view in side elevation of the automatic liquid dispenser when the casing is open to disclose the interior parts, some of which are broken away and some of which are shown sectioned.

Figure 1A is an elevational view of a fragment of the structure shown in Figure 1.

Figure 2 is a view in front elevation of a portion of the mechanism shown in Figure 1, the casing being removed to disclose the interior structure.

In my present arrangement the oil or other liquid is to be stored in an underground container which is not shown. The outlet pipe 10 of this container is connected with a pump 11 of any desired form. In the present instance the pump as shown is the ordinary lifting pump having added thereto a spring or a weight for returning the piston to its lowermost position. The piston 12 with its valve 13 and the piston stem 14 are of common construction and they may be varied at will. The outlet of the pump is shown at 15 to which may be attached any suitable hose connection for delivering the oil or other liquid di-

rectly into a receptacle or into the crank case of the automobile. Thus far the features are of common construction which have been well and widely known for many years. The part shown in the drawing and especially those parts above the bottom of the pump casing 11 are above ground and so positioned that the delivery hose is at a convenient height.

The pump is actuated by means of a rack 16 which is firmly secured to the piston stem 14, the rack being operated by means of a pinion 17 which may be turned by means of a hand crank 18 or by a motor or any other suitable source of power. By turning the pinion 17 in a counter-clockwise direction as viewed in Figure 1, the rack 16 will be elevated and this will carry with it the piston 12 to deliver the liquid through the outlet 15. The rack 16 is lowered by means of a spring 19 within the pump casing 11 to thus dispense with the necessity of lowering the rack 16 by turning the pinion 17. The hand crank 18 is secured to a drum 20 which is slidable on the shaft 21. The drum 20 interlocks at 22 with a drum 23 which is keyed or otherwise secured to the shaft 21 for elevating the rack 16. The drum 20 is moved into interlocking engagement with the drum 23 in the position shown in Figure 2. For reverse movement of the rack 16 the drum 20 may be drawn away from the drum 23 so that the rack may be lowered without the necessity of turning the crank 18.

The rack 16 is provided with a latch which normally holds it against upward movement. This latch consists of a notch in the rack for receiving the end of the detent 24. This detent is slidably mounted in a socket containing a spring 25, the spring normally urging the detent into engaging position. Before the rack 16 can be raised, the detent 24 must be released from its engagement with the rack. This release must be against the action of the spring 25 and the detent must be held at least temporarily in released position. The detent is therefore provided with a corner cutaway portion 26 for receiving a second detent 27. The detent 27 is freely slidable in the supports 28 and 29, the support 29 being hollow and containing a spring 30 which urges the detent 27 into engagement with the detent 24. It is obvious that when the detent 24 is pushed back against the action of the spring 25 a sufficient distance to clear the detent 27, the detent 27 will drop into the notch 26 to hold the detent 24 out of operative position.

The means for releasing the detent 24 from engagement with the rack 16 includes mechanism 110

which is operated partly by means of a coin. A spring pressed plunger 31 is provided at one end with a head 32 and at the other end with a button 33 so that it may be pressed inwardly by pressure of the thumb on the button 33. The head 32 is in axial alignment with the detent 24 but these two parts are spaced apart. In order to close the gap between the head 32 and the detent 24, a coin must be inserted and the coin must be pushed into engagement with the detent 24. The coin, which is shown in outline in its different positions at 34, 34a, and 34b, first enters the mechanism through a chute 35 and then seats against the curved face of the head 32. By pushing on the button 33, the coin is moved through its successive positions first into engagement with the end of the detent 24 and then to push the detent 24 a distance sufficient to clear it of the detent 27. The plunger 31 will immediately resume its normal position and this will then allow the coin to fall away from the detent 24 since the pressure on the coin is removed when the pressure of the head 32 on the coin is released. The passageways for the coin may be varied in numerous ways but in the present instance I have shown an entrance chute 35 with a delivery chute 36 for conducting the coins to any suitable coin box. The action of the coin and of the plunger 31 is such that it releases the rack 16 from latching engagement so as to permit the turning of the shaft 21 to operate the pump.

Secured to the shaft 21 are two ratchets 37 and 38. These ratchets are opposing ratchets and they are engageable by the pawls 39 and 40 respectively. These two pawls are so arranged that one or the other of them must be in engagement with its respective ratchet while the other pawl is idle. When the pawl 40 is in engagement with the ratchet 37, the shaft 21 may be turned in a direction to elevate the rack 16 but the shaft can not be turned in a direction to lower the rack 16. Since the purpose of the invention is to provide a coin operated releasable latch for the rack 16, provision must be made for preventing unscrupulous operators from turning the crank 18 alternately in both directions to thus obtain all the oil that they need by the mere payment of a single coin. The pawl and ratchet mechanism as above described is so arranged that reciprocatory partial movements of the rack 16 are impossible.

The pawls 39 and 40 are integral parts of a pawl frame which is pivotally connected for rocking movements about the point 41, the fixed support being shown at 42 which may be U-shaped as shown in Figure 2. This pawl frame has an arm 43 which is connected by means of a tension spring 44 to a fixed portion of the frame at 45. The spring 44 normally urges the pawl 40 into engagement with the ratchet 37. The rack 16 in its lower portion has an arm 46 extending laterally and having a vertical path of movement parallel to that of the rack 16. The arm 46 is so positioned that the arm 43 is in its path of movement. When the rack 16 approaches the upper limit of its movement it comes in contact with the arm 43 to rock the pawl frame against the tension of the spring 44. The rocking of the pawl frame immediately releases the pawl 40 from engagement with the ratchet 37 and forces the pawl 39 into engagement with the ratchet 38. Further upward movement of the rack 16 is then impossible but the rack 16 is free to move downwardly in response to the pull of the spring 19.

While the rack 16 is free to move downwardly after the pawl frame has been tripped through contact with the arm 46, the pawl frame would tend to be again tripped under the tension of the spring 44 as soon as the arm 46 is out of contact with the arm 43 and this would stop further downward movement of the rack 16. An additional latch must therefore be provided for maintaining the position of the pawl frame until the rack 16 reaches its lowermost position. This additional latch includes an arm 47 having a hooked end 48 and an arm 49 having a hooked end 50. The arm 47 is integral with the pawl frame while the arm 49 is pivotally secured at 51 to a fixed part of the casing. An expansion spring 52 is interposed between the arm 49 and a fixed portion of the casing, its purpose being to urge the arm 49 toward the arm 47. This movement is limited by means of a fixed stop 53. A movable stop 54 is also employed, this being L-shaped as shown in Figure 2 and secured to the rack 16 at or near its upper extremity. When in the position shown in Figure 1 the stop 54 prevents forward movement of the pivoted arm 49. As the rack 16 rises, the stop 54 will clear the arm 49 so that the arm 49 is free to move into contact with the arm 47. The hooked end 50 is, however, at a slightly higher level than the hooked end 48 so that engagement of the hooked ends with each other is impossible during the upward movement of the rack 16. When, however, the arm 46 engages the arm 43 to trip the pawl frame, the hooks 48 and 50 are brought into engagement with each other to hold the pawl frame in a position to permit the continued downward movement of the rack 16. When the rack approaches the limit of its downward movement the stop 54 will engage the arm 49 to release the hook 50 from engagement with the hook 48.

At the beginning of the operation the detent 24 was withdrawn from the notch in the rack 16 and it was latched against reengagement. In order to operate successfully for the purpose intended, it is necessary that the detent 24 be released to again enter the notch of the rack 16 when the detent and notch are in alignment so as to lock the apparatus against further operation until another coin has been inserted. The detent 27 is provided with an arm 55 while an arm 56 is secured to the piston stem 14, the arm 55 being in the path of the free end of the arm 56. When the arm 56 in its upward movement contacts with and bears against the arm 55, it will push the detent 27 upwardly against the action of the spring 30 to thus release the detent 24 which is then free to slide into the notch in the rack 16.

The vender is to be used with a selective coin mechanism of any desired type. The coin is discharged from this mechanism through the chute 35 to its seat against the head 32 after which the purchaser first pushes the plunger 31 and then turns the crank 18. All other movements are automatic.

The vender is designed initially and primarily for dispensing lubricating oil to motorists. It may be used without change for dispensing alcohol or other liquids which are measured in similar units and which are used by the motorist. With slight changes in the dimensions it may be used for vending gasoline. In other lines of business the vender may be employed for dispensing other liquids.

Having thus described my invention in such

full, clear, and exact terms that its construction and operation will be readily understood by others skilled in the art to which it pertains, what I claim as new and desire to secure by Letters Patent of the United States is:

1. In a vender for liquids, a pump having a piston, means for normally urging said piston into its lowermost position, a rack secured to said piston and extending upwardly therefrom, a pinion meshing with said rack for elevating said rack, a pair of opposed ratchets associated with said pinion, a pair of pawls engageable one at a time with the respective ratchets, and automatically operable means at the respective ends of said rack for tripping said pawls at the end of each upward or downward stroke to thereby prevent reverse movement of said rack before the completion of the stroke.
2. In a vender for liquids, a pump having a

piston, a rack secured to said piston and extending upwardly therefrom, a pinion meshing with said rack, a pair of opposed ratchets secured to said pinion, a pivoted pawl frame having a pair of pawls integral therewith for engagement one at a time with said opposed ratchets, a spring for normally maintaining said pawl frame in position to prevent downward movement of said rack, an arm on said rack for tripping said pawl frame at the end of the upward stroke of said rack to thereby release said rack for downward movement and to latch said rack against further upward movement, a pivoted latch for engaging said pawl frame after it has been tripped by said arm, and a second arm on said rack for releasing said pivoted latch from engagement with said pawl frame at the completion of the downward stroke of said rack.

JOHN M. ALEXANDER.
